one-half to Walter W. Winchenbach, South
Portland, Maine

Application December 24, 1938, Serial No. 247,676

5 Claims. (Cl. 137—20)

The invention hereinafter to be described relates, in general terms, to siphon apparatus, but deals more particularly with improvements therein embodying structure by means of which the siphonic action is started without resort to raising the pressure above that of the atmosphere in the vessel to be discharged of liquid, and by which, once the evacuation operation begins, the apparatus can be maintained in "primed" condition for an indefinite period of time.

A conventional method of operating siphon devices, particularly where the liquid is to be discharged from large vessels having small mouths, is to first create a gage pressure within the vessel 15 the mouth of which is temporarily closed, and rely on this pressure to prime the discharge-tube to start the siphoning, means being provided to air-vent the vessel from which the liquid is being removed immediately after the drafting action starts.

In the particular application which I have chosen to disclose my invention, and in connection with which I will illustrate and describe it, development of any gage pressure in the container to be discharged of liquid is prohibitive, as in this instance the liquid-holding vessel is a glass carboy in which the highly corrosive acids, such as sulphuric, nitric, muriatic and others are marketed and from which the acid is drawn, 30 usually in small quantities, by the purchaser to fill his immediate needs.

The carboys are large glass vessels usually of about thirteen gallons capacity, with large bottle neck tops. They are shipped from the factory 35 where the acid is made enclosed in wooden boxes or crates, carefully packed and filled with the dangerous-to-handle chemicals.

It is due largely to the more or less fragile character of these large glass acid containers that manufacturers of acids or other corrosive liquid chemicals do not approve of siphon apparatus 40 for use in connection with handling their product which employ gage-pressure means for priming them.

I have no intention, at this time, to discuss in detail the prior art, further than to point out the fact that from the standpoint of those upon whom devolves the duty of removing these dangerous chemicals from carboys the heretofore available apparatus has been adjudged deficient and unsafe.

My present invention, briefly stated, embodies an integrally formed tubular structure combining a draft-tube and a discharge-tube. The draft-tube has mounted thereon a vented rubber cap

which encloses the mouth or top end of the carboy.

Concentrically disposed on the discharge-tube is an observation cylinder with a bushing at each end tightly filling the annular space between the discharge-tube and cylinder wall.

A retractile rubber bulb has connection with the observation cylinder through a nipple in which is a float valve adapted to come to a seat in the nipple when liquid rises to a predetermined level in the cylinder, at which time no further inflation or deflation of the bulb can take place.

An aspirator or breathing valve is located at the outer end of the bulb and operates to prevent admission of outside air to the bulb after each deflation thereof.

Proper means are provided at the lower end portion of the discharge-tube to regulate and control the outflow of the liquid from the apparatus, the means being entirely out of contact with the liquid passing through and remaining in the discharge-tube.

For a clearer understanding of the import of my invention reference should be had to the description found in the following specification, when taken in connection with the accompanying drawing disclosing an embodiment which, at the present time, I consider preferable to other possible forms in which the invention might be carried out.

In the drawing, in which like reference characters indicate like parts in all the different views—

Fig. 1 shows the apparatus mounted on an acid-holding carboy, in operative position;

Fig. 2 is a section on line 2—2, Fig. 1;

Fig. 3 is a sectional elevation of the observation cylinder showing the operating bulb and float valve holding element;

Fig. 4 shows the discharge hose clamp positioned to give full capacity outflow of discharge-tube;

Fig. 5 is like Fig. 4, except that the discharge hose is completely shut off;

Fig. 6 is a section on line 6—6, Fig. 4;

Fig. 7 is a sectional elevation of the float valve nipple within which is shown the hollow float valve;

Fig. 8 is a section on line 8—8, Fig. 3, and

Fig. 9 is a perspective view of the rotatable closing element for the fixture shown in Figs. 4 and 5.

In the drawing, 1 represents a wooden box—the shipping container for the glass carboy 2 in which

acids or other dangerous liquid chemicals 3 are transported.

The neck end 2a of the carboy projects through the top of the box, and covering closely the mouth 2b of the carboy is a soft rubber semi-spherical cap 4 engaging the enlarged end 2c of the neck and largely preventing escape of acid fumes from the carboy. The cap may be repositioned, vertically, on and for different lengths 10 of draft-tubes and holds the latter centrally of the mouth 2b of the carboy. The cap has an air-vent at 4a.

Rising from the bottom interior portion of the carboy is a draft-tube 5. After passing through 15 the portion 4b of the cap the draft-tube bends in an easy curve and turns downwardly to become the discharge-tube 6 of the apparatus.

At a predetermined distance from the uppermost part of the tubular structure a glass observation cylinder 7 is concentrically mounted on the discharge-tube 6. The cylinder has a bottle end neck 8 in which is an opening 8a. The discharge-tube 6 passes downwardly through this opening, and in the annular space between the 25 discharge-tube and the neck of the bottle end of the cylinder is a tightly fitting, acid-resisting bushing 9, made of somewhat compressible material to insure a leak-tight joint between the parts.

30 The lower end portion of the cylinder 7 and its neck portion 8 is protected by a rubber cap 10, and its upper end is likewise protected by another rubber cap 11. The intermediate portion of the cylinder is covered with a coarse wire 35 screen 12.

A port hole or opening 13 in the wall of the discharge-tube provides communication between the interiors of discharge-tube 6 and the cylinder 7, the opening being at the bottom of the chamber C so that the latter can be fully drained when de-priming the apparatus.

40 The upper end of the cylinder 7 has a tight fitting, acid-resisting bushing 14, through a hole 14a in which passes the discharge-tube 6, the latter also making an air and liquid tight fit in the bushing.

45 The members 11 and 14 are perforated to receive with a leak-proof fit the float-valve nipple 15. The nipple depends into the chamber C in the cylinder 7, and the upper portion of the nipple extends upwardly out of the member 11 sufficiently far to permit mounting thereon the lower shank end 16a of the retractile bulb 16.

If reference be had to Fig. 7 it will be observed 50 that the glass nipple 15 is open throughout its length and that intermediate its ends is a ground seat 15a.

55 Within the compartment D of the nipple 15 is a hollow glass float-valve 17 the upper end 17a of which is also ground to make an air and liquid tight joint when the float-valve rises into engagement with the seat 15a. The lower end of the nipple, 15b, is drawn inwardly a slight amount in order to prevent outward displacement of the float-valve, this operation, of course, being performed after first inserting the float-valve in compartment D.

70 The lower end 17b of the float-valve is flattened so as to provide ample space for air to pass upwardly by it in the operation of priming the discharge-tube.

75 On the upper shank end of the rubber bulb 16 is mounted structure shown in sectional detail in Fig. 8. Around the shank 16b of the bulb is a thick rubber sleeve 18, and seated in the upper

end of this sleeve is an aspirator or breather valve 19. Across the opening 16c of the shank 16b is a bar 20 and connecting this bar with the valve 19 is an elastic rubber cord 21. The function of this valve 19 will hereinafter be explained.

5 After passing downwardly through the observation cylinder 7, the discharge-tube 6, which may be made of any acid-resisting material, such as glass, metal, or any one of various acid-resisting compounds, makes connection with a pliable 10 rubber hose or tube 22, on which is mounted a tube clamp device designed to control the discharge or rate of outflow of the liquid from the apparatus.

15 The tube clamp comprises a rectangular shape, open-side member 23 having lateral inwardly disposed flanges 23a on which is slidably mounted a tube 24 having on each end two slots 24a cut diametrically of the tube and straddling, respectively, the lateral flanges 23a.

20 On the tube 24 is a rotatable sleeve 25 which contacts the soft, pliable rubber tube 22 and acts to progressively reduce the effective rate of outflow of the liquid from the apparatus as it is moved toward the narrower end of the hose 25 clamp, and conversely, to increase this outflow as it is slid along the clamp from the narrower toward the wider end portions thereof.

25 Fig. 4 shows the outflow-control sleeve positioned for maximum discharge of the liquid, and Fig. 5 depicts it in a position in which the discharge is completely stopped. Intermediate positions of the sleeve on the clamp give corresponding degrees of opening of the hose and discharge of the liquid. The expansibility of the tube 22 35 acts to frictionally hold the sleeve 25 in any location in which it is placed between its extreme positions. The ends of the flanges 23a are bent over at 23b so as to retain the tube 24 thereon.

30 In operating my siphon apparatus, after first 40 being placed in position as shown in Fig. 1, the bulb 16 is deflated by compressing it, the air mostly flowing outwardly through the opening 16b after having raised the valve 19 off the seat 18a.

45 A comparatively small amount of the air may pass downwardly through the nipple 15 into chamber C and thence into the carboy 2. But no pressure develops in the carboy as it is air-vented at 4a. The discharge-tube is closed at this 50 time.

55 Now upon release of compression of the bulb, permitting it to inflate, or regain its original shape, the air within it is rarefied and this immediately starts a suctional action in the air line, and the liquid in the carboy starts upwardly in the draft-tube 5. It may be necessary to repeat the compression of the bulb operation, depending on the comparative areas of the bulb and tube interiors; but eventually the displacement of the 60 air by the liquid will prime the discharge-tube and the siphon action starts, immediately the discharge-tube is opened.

65 Each deflation operation on the bulb opens the valve 19 and the subsequent inflation action closes it. After the siphonic movement of the liquid is under way the valve 19 is yieldingly held on its seat by the rubber cord 21, and unless this valve is moved off its seat by further deflation of the bulb or manual actuation thereof, the liquid will 70 continue to discharge from the apparatus by siphon action, provided, of course, the hose clamp 23 is positioned to open the tube 22.

75 It will be understood that in priming the discharge-tube in the first operation, the hose clamp

closes the tube 22 until the discharge-tube 6 is filled. Thereafter, the liquid may be withdrawn from the carboy at intervals, or continuously without the necessity of re-priming.

5 In the course of priming the apparatus the liquid will enter the hole 13 and rise a short distance in the chamber C, say to line $w-w$, sealing the hole against entrance of air from the chamber C into the discharge-tube 6. With a tight fitting aspirator valve and the discharge-tube closed, the apparatus will remain primed for a considerable length of time.

Occasionally, however, the operator of the apparatus will either accidentally or unconsciously 15 continue the deflation operation on the bulb further than is necessary, and then the liquid will continue to rise in the chamber C; and were there no means provided to prevent it, it would even fill the bulb 16 with consequent danger of 20 escaping and injuring the operator.

But at this point the float-valve in the nipple 15 functions, and should the liquid rise to say the level of line $z-z$, the float-valve will rise to the seat 15a, and close access to the bulb. Should 25 further deflation of the bulb be made, it will not inflate due to the fact that the rarefied air in the bulb will hold both the valves 17 and 19 on their seats. The operator would, under these 30 circumstances, be unable to further deflate the bulb as it remains deflated, unless the valve 19 is manually raised off its seat, breaking the vacuum in the bulb.

The automatic method of control of the rise 35 of the liquid in the observation cylinder is a very important feature in my improved siphon apparatus, as it eliminates one cause for serious injury to the workman which frequently occurs in using siphon devices of conventional construction.

40 Another appealing feature resides in the very simple and conveniently actuated discharge control elements which are operated with one hand, the hose clamp member being held by the fingers 45 in the palm of the hand while the thumb moves the revolving sleeve up and down on the inclined faces of the clamp.

De-priming of the apparatus is easily accomplished by lifting the valve 19 into the dot 50 and dash line position shown in Fig. 8 and opening the hose clamp for free entrance of air into the discharge-tube.

What I claim is:

55 1. A siphon equipment comprising an inverted, U-shape tubular member combining the draft and discharge-tube elements thereof, an observation cylinder disposed on and concentrically with said discharge-tube, said discharge-tube having in its wall a relatively fixed opening through which communication between its interior and that of said observation cylinder may be had, said opening being located considerably below the union point of the two said tube elements, caps mounted on the top and bottom ends, respectively, of said observation cylinder, a float-valve nipple having a valve seat therein, extending into the interior of said observation cylinder and rising above the upper of the two said caps, a float-valve disposed within said nipple, adapted to engage said seat only when liquid entering said observation cylinder rises to a predetermined level therein, a retractile bulb on the upper end of said nipple, an aspirator valve on the upper end of said bulb, means for manually actuating said aspirator valve for depriming said siphon

equipment, and means to open and close said discharge tube predeterminedly.

2. In a siphon equipment for acid-holding carboys the combination with an integral, two-leg tubular member, one leg thereof constituting a 5 draft-tube extending downwardly into said carboy, and a vented cap mounted on said draft-tube and disposed over the mouth of said carboy, of an observation cylinder on the other of said legs, said last mentioned leg constituting the 10 discharge-tube of said tubular member, means for inter-communication between the interiors of said discharge-tube and said observation cylinder, said means being disposed at an elevation 15 of the two legs of said tubular member, a retractile bulb, a valve, opening outwardly, yieldingly mounted in the upper end of said retractile bulb, means on said valve for manually raising it from off its seat, interior communication means 20 between said bulb and said observation cylinder and a valve seating in a direction opposite to that of said first mentioned valve adapted to close said interior communication means when liquid entering said observation cylinder reaches 25 a predetermined level therein.

3. A siphon equipment comprising in combination with a draft-tube and an interconnecting discharge-tube, a closure member on the lower end portion of said discharge-tube, a cylindrical 30 member through which said discharge-tube tube passes leaving a space within said cylinder closed at both ends, an aperture in the wall of said discharge-tube opening into said space and fixed relative to said cylinder, a nipple having 35 a valve seat intermediate its ends, projecting into said space, a float-valve in said nipple closing, only, when liquid in said nipple causes the valve to rise to its seat in said nipple, means to rarefy the air in said cylinder space, said means being 40 connected at one end to the outer end of said nipple, "and a valve, seating inwardly, disposed at the opposite or outer end of said air rarefying means.

4. A siphon equipment for transferring liquid 45 from one vessel to another comprising a draft-tube insertable in the liquid containing vessel, a discharge-tube connecting therewith, a glass cylinder, closed at both ends, concentrically mounted on said discharge-tube, forming an 50 annular space having communication with the interior of said discharge-tube, a retractile bulb having, normally, interior communication with said annular space, means to close communication between said bulb and said annular space when, 55 in the course of priming said equipment, the liquid rises to a predetermined elevation in said glass cylinder, an aspirator valve on the outer end of said retractile bulb, seating inwardly, a pliable hose secured on the lower end of said 60 discharge-tube, and a hose clamp mounted on said hose, adapted to control the outflow of liquid therefrom.

5. In a siphon equipment for transferring liquids from one container to another, the combination, with a draft tube and an interconnecting discharge tube having means for closing its lower end, of a glass observation cylinder mounted on and enclosing a portion of said discharge tube, forming a chamber, an aperture in the wall of 70 said discharge tube supplying communication between said discharge tube and said chamber, protective means for said observation cylinder, a nipple, a portion of which is disposed in and has interior communication with said chamber, a 75

valve seat in said nipple, a float valve in said nipple adapted to engage said seat and close the passage-way through said nipple only when the liquid in said chamber rises to a predetermined level therein, raising the valve to its seat, a retractile bulb making connections with said nipple, one air valve only in said bulb, located

at its outer end, opening upon the bulb being compressed, a spindle on the valve in said bulb for manually lifting it off its seat, and yieldable means for holding said valve in an off-its-seat position while depriming the siphon.

WILLIS F. THOMPSON.
